F. L. COOLEY.
REFILLABLE CARTRIDGE FUSE.
APPLICATION FILED JAN. 8, 1919.

1,362,230.

Patented Dec. 14, 1920.

UNITED STATES PATENT OFFICE.

FRANK L. COOLEY, OF BROOKLYN, NEW YORK.

REFILLABLE CARTRIDGE-FUSE.

1,362,230.

Specification of Letters Patent. Patented Dec. 14, 1920.

Application filed January 8, 1919. Serial No. 270,113.

To all whom it may concern:

Be it known that I, FRANK L. COOLEY, a citizen of the United States, residing at Brooklyn, in the county of Kings and State of New York, have invented certain new and useful Improvements in Refillable Cartridge-Fuses; and I do hereby declare the following to be a full, clear, and exact description of the invention, such as will enable others skilled in the art to which it appertains to make and use the same, reference being had to the accompanying drawings, and to characters of reference marked thereon, which form a part of this specification.

The present invention has reference, generally, to improvements in cartridge fuses; and the invention relates, more particularly, to a novel construction of refillable cartridge fuse.

The invention has for its principal object to provide a novel and simple construction of refillable cartridge fuses involving improved structural features to accomplish the following objects, to wit: to provide improved means for securing the removable end ferrules, both to the ends of the casing in sealing relation to the chamber thereof, and in proper electrical contact with the fuse arranged within said casing; to provide an efficient support and disposition of the fuse link within said casing so as to properly center the blowing portion thereof; and to provide for other objects, not at this time more particularly enumerated, but which will be clearly understood from the following detailed description of the present invention.

With the various objects of the present invention in view, the same consists, primarily, in the novel construction of refillable cartridge fuses hereinafter set forth, and the invention consists, furthermore, in the novel arrangements and combinations of the various devices and parts, as well as in the details of the construction of the same, all of which will be hereinafter more fully described, and then finally embodied in the claims appended to this specification.

The invention is clearly illustrated in the accompanying drawings, in which:—

Figure 1 is a side elevation of the novel construction of a refillable cartridge fuse made according to and embodying the principles of my present invention; Fig. 2 is an end elevation of the same; Fig. 3 is a longitudinal vertical section through the same,

taken on line 3—3 in said Fig. 1, said view being drawn on an enlarged scale; Fig. 4 is another longitudinal section through the same, taken on line 4—4 in said Fig. 3; Fig. 5 is a detail side elevation of one end of the cartridge casing showing the ferrule thereon broken away to show the mortised seat provided for the cross nut of the ferrule fastening devices; and Fig. 6 is an end elevation of the cartridge fuse, with an end ferrule removed therefrom.

Fig. 7 is a detail longitudinal vertical section, similar to that shown in Fig. 3, but illustrating the arrangement of knife-blade contact elements in connection with the ferrules of the cartridge fuse; Fig. 8 is another longitudinal section, taken on line 8—8 in said Fig. 7; and Fig. 9 is an end view of said construction, with the ferrule removed, and the position of the knife-blade contact element indicated in broken outline.

Similar characters of reference are employed in all of the hereinabove described views, to indicate corresponding parts.

Referring now to the said drawings, the reference-character 1 indicates a tubular casing, made of some suitable insulating or non-conducting material, which provides an interior fuse chamber 2.

Provided in the walls at each end of said casing 1 are a pair of transversely opposite mortised seats 3, the sides 4 of which incline inwardly toward the outer end of the casing. Dovetailed into said respective mortised seats 3 are the ends of a transversely disposed cross nut or anchor bridge 5, which is shaped in cross-section to correspond to the shape of said mortised seats, and which may be thrust or withdrawn endwise from said seats, but is held, by engagement in said seats, against outward displacement or withdrawal from the open ends of the said casing 1. Said cross nut or anchor bridge 5 is provided with a centrally disposed internally threaded opening 6.

The reference-character 7 indicates a removable fuse link, provided with end terminals 8 having perforations or openings 9 therein. Said fuse link, when properly assembled, passes longitudinally and diagonally through the fuse chamber 2, with its end terminals 8 extending over the cross nuts or anchor bridges 5, one terminal passing over the upper side of one cross nut or anchor bridge, and the opposite terminal passing under the lower side of the opposite

cross nut or anchor bridge, thus assuring the diagonal disposition of the main body of the fuse link within the fuse chamber, so that the intermediate blowing portion thereof (subsequently described) is assured of being centered in position intermediate of the inner sides of the walls of said casing 1. The respective end terminals 8 are turned over the outer faces of the respective metallic cross nuts or anchor bridges 5, with their perforations or openings 9 alined over the internally threaded openings 6 of said cross nuts or anchor bridges. Connected integrally with one of said end terminals 8 of said fuse link 7 is an indicator tongue 10 adapted to extend over the marginal edge of the adjacent end of said casing 1, so as to be doubled back over the exterior side of said casing 1 in such a manner that its free end 11 is visibly exposed against the exterior side of said casing 1 beyond the free marginal edge of the skirt of a ferrule (subsequently described) which is arranged over said end of said casing 1. Inscribed on said free end 11 of said indicator tongue is an indicating mark 12 denoting the amperage capacity of the fuse link 7. This feature of the construction of my novel refillable cartridge fuse is of peculiar advantage, in that the fuse link itself bears the indication of its electrical capacity, in such manner as to be externally visible when the fuse link is properly assembled with the cartridge. In consequence of this novel arrangement the user of the cartridge fuse or the inspector charged with the duty of seeing that proper capacity fuses are used, is always assured that only a fuse link of a proper capacity for the conditions required of the cartridge fuse is employed, and mistakes in the replacement of fuse links are rendered less likely of occurrence.

The reference-character 13 indicates the metallic external contact ferrules, the annular skirts 14 of which are telescopically engaged over the ends of the casing 1. Said ferrules 13 are adapted to close the ends of the casing 1, and at the same time electrically engage the end terminals 8 of the fuse link 7. Said ferrules 13 are constructed in a novel manner for the purpose of so engaging the open ends of the casing 1 as to securely seal the latter against the escape of flame therefrom when the fuse link blows, and at the same time the novel construction is such that a secure clamping of the end of the ferrules against the end terminals 8 of the fuse link, as the said terminals are backed by the cross nuts or anchor bridges 5, is assured, whereby an efficient and certain electrical contact of the ferrules with the fuse link is attained. To this end each ferrule 13 is provided in its end wall with an inwardly depressed and tapered concentric boss 15, the periphery 16 of which is

carried into engagement with the marginal edge 17 of the opening of the casing ends in a sealing relation thereto in much the same way as a cork or stopper is engaged in the neck of a bottle. The transverse wall 18 of said boss 15 is provided with a centrally disposed perforation 19, which, when the ferrule is in place, alines itself with the internally threaded opening 6 of said cross nut or anchor bridge 5, and the opening 9 of the end terminal 8 of the fuse link registered with the said threaded opening 6. A fastening screw 20 is inserted through said perforation 19, so as to pass through said opening 9 of the fuse link terminal 8, and thus into threaded relation to the opening 6 of the cross nut or anchor bridges. The head 21 of said screw 20 engages the outer surface of said transverse wall 18 of the boss 15. When the screw 20 is screwed home it draws down the ferrule against the end of said casing 1 so as to first wedge the boss 15 securely into the open end of the casing 1 in sealing relation thereto, and then by inwardly depressing said transverse wall 18 forces the same firmly into certain electrical contact with the adjacent end terminal 8 of the fuse link, securely clamping the same between said transverse wall 18 and the outer face of said cross nut or bridge anchor 5 over which it is engaged. The ferrule 13 engaged over the end of the casing 1 at which the indicator tongue 10 of the fuse link is located, freely slides over said indicator tongue 10. The said indicator tongue 10, however, is of sufficient length that its free end 11 projects beyond the free edge of the skirt of the ferrule, when the latter is secured in final assembled relation, so that said free end 11 is visibly exposed against the exterior side of the casing in a manner clearly disclosing the fuse capacity indication mark 12 inscribed thereon. The fastening screw 20 being free to turn in the opening 19 of the transverse wall 18 of the ferrule boss 15, there is no turning or twisting movement imparted to the ferrule when being fastened in place thereby, and consequently no twisting or straining movement is imparted to the fuse link end terminals 8 tending to distort the same, or by fracture or breakage at such point tending to alter the fuse capacity.

The fuse link 7 is provided intermediate of its end terminals 8 with two or more longitudinally spaced perforations 22 of properly predetermined diameter relative to the width of the fuse link body. These perforations thus disposed determine the size of blow out portions 23 of the fuse according to the amperage capacity desired of the fuse link, and at the same time assure, as far as is practically possible, that the fuse will blow at such points well withdrawn and centered within the interior of the fuse

chamber 2 of the casing 1, thus avoiding likelihood of fusing the end terminals 8 to the ferrules or fastening means thereof, whereby disassembling of the said parts is 5 prevented.

In the event an assembled fuse link blows when the cartridge is in use, the cartridge may be removed from the electric circuit it serves, and the ferrules taken off so that 10 the blown fuse link may be removed, and a new replacement thereof made, whereupon the ferrules are again assembled in the above described relations to the renewed cartridge. It will also be clear that the novel construction of cartridge fuse above described comprises comparatively few parts of simple, 15 strong and durable construction and arrangement, very easily manipulated for purposes of renewing the same after it is blown. 20 The same being so arranged that the interior fuse chamber 2 is practically sealed against the venting of flame therefrom upon the blowing of the fuse, so that not only does the cartridge fuse provide a high order of 25 electrical efficiency when in use, but also provides a maximum of safety from all other standpoints.

I am aware that some changes may be made in the arrangements and combinations 30 of the various devices and parts, as well as in the details of the construction of the same, without departing from the scope of my present invention as set forth in the foregoing specification, and as defined in the 35 appended claims. Hence, I do not limit my invention to the exact arrangements and combinations of the several devices and parts as described in the foregoing specification, nor do I confine myself to the exact details 40 of the construction of the said parts so illustrated in the accompanying drawings.

I claim:—

1. A refillable cartridge fuse comprising a tubular casing having transversely opposite mortised seats in the ends of its walls, 45 transverse cross members fixed within the open ends of said casing by dovetailing their ends into said mortised seats, a fuse link having end terminals engaged over said cross members, removable contact ferrules 50 slidable over the ends of said casing, said contact ferrules having means engaging the open ends of said casing to seal and close the same, and fastening means adapted to secure said ferrules 55 respectively to said cross members and in electrical engagement with the end terminals of said fuse link.

2. A refillable cartridge fuse comprising 60 a tubular casing having transversely opposite mortised seats in the ends of its walls, transverse cross members fixed within the open ends of said casing by dovetailing their ends into said mortised seats, a fuse link

having perforate end terminals engaged 65 over said cross members, removable contact ferrules slidable over the ends of said casing, the end walls of said ferrules having inwardly depressed bosses the peripheries of which are adapted to be pressed into 70 sealing relation to the open ends of said casing, the transverse walls of said bosses having openings therein, and loose fastening screws adapted to be passed through said openings and thence through said fuse 75 link terminals to screw into said cross members whereby said bosses are drawn to said sealing relation to the ends of said casing, and said transverse walls of said bosses depressed into electrical contact and mechanically clamping relation to said fuse link terminals. 80

3. A refillable cartridge fuse comprising a tubular casing having transversely opposite indented notches in the ends of its 85 walls, the sides of said notches being restricted toward their open ends, cross members of outwardly tapered cross-sectional shape, said cross members being movable endwise into said notches so that their ends 90 dovetail into the latter to be thereby held against outward withdrawal from the ends of said casing, a fuse-link extending through said casing having its ends engaged respectively over said cross-members, removable 95 contact ferrules slidable over the ends of said casing to retain said cross-members against endwise removal therefrom, means connected with said ferrules for sealing the ends of said casing, and detachable fastening screws adapted to screw into said cross-members for securing said ferrules in sealing relation to said casing and in electrical contact with the ends of said fuse-link as engaged over said cross-members. 100

4. A refillable cartridge fuse comprising a tubular casing having transversely opposite indented notches in the ends of its walls, the sides of said notches being restricted toward their open ends, cross-members of outwardly tapered cross-sectional shape, said cross-members being movable endwise into said notches so that their ends dovetail into the latter to be thereby held against outward withdrawal from the ends 110 of said casing, a fuse-link having end terminals respectively engaged over opposite sides of said cross-members so that the body thereof passes diagonally through the interior of said casing, removable contact ferrules slidable over the ends of said casing, the same serving to retain said cross-members against endwise removal from said notches, the end walls of said ferrules having depressed bosses the peripheries of 115 which are adapted to be pressed into sealing relation to the open ends of said casing, and detachable fastening screws adapted to 120 125

pass through said bosses and fuse link terminals to screw into said cross-members whereby said bosses are drawn to sealing relation to said casing and at the same time 5 depressed into electrical contact and mechanical clamping relation to said fuse link terminals.

In testimony that I claim the invention set forth above I have hereunto set my hand this 20th day of December, 1918.

FRANK L. COOLEY.
